SAFETY SUPPORTING MEANS FOR BRAKE BEAMS

Seth A. Crone, East Orange, N. J., assignor to
 Buffalo Brake Beam Company, New York,
 N. Y., a Corporation of New York

Application April 21, 1931. Serial No. 531,705

9 Claims. (Cl. 188—210)

For a clearer understanding of the present invention, reference may be had to my prior U. S. Letters Patent No. 1,708,121, dated April 9, 1929, wherein there is disclosed an emergency safety bar of one piece which has a bearing relation with the bottom surface of a spring plank and wherein there are disclosed two brackets which depend from the spring plank and by means of removable locking pins are adapted to support the safety bar in position.

However, in that patent the brake beams are approximately in the plane of or slightly above the plane of the bottom of the spring plank, and the patented construction as specifically disclosed is not adapted for use with a safety bar having its outer ends extended upwardly and located above the bottom of the spring plank, whereby to support brake beams differently positioned from what is disclosed thereby. 20 In such a case as the latter it is desirable to make the safety bar in two sections, each of which may be separately supported in using position.

The present invention therefore contemplates the provision of means whereby two similar bar members may be separately detachably supported underneath the spring plank, for separate assembly therewith, the inner ends of the bar members being detachably connected together. In carrying out such object of the present invention it is preferred to extend portions of the supporting brackets inwardly so that they will have a bearing relation with the bottom of the spring plank, and to overlap the inner ends of the bar members and connect them by means of a suitable member which is removably pinned to the overlapped ends, such connecting member preferably bearing upon the bottom surface of the spring plank.

40 With these and other objects in view, the present invention consists of certain novel features of construction and combinations of parts to be hereinafter described and then claimed with reference to the accompanying drawing illustrating a preferred embodiment of the invention and wherein

50 Figure 1 is a fragmentary top plan of a brake beam mechanism provided with safety bars in accordance with the present invention;

55 Fig. 2 is an enlarged plan of a portion of a spring plank, showing the present improvements;

Fig. 3 is a transverse section on the line 3—3, Fig. 2, and the improved means shown in elevation;

Fig. 4 is a broken detail section on the line 4—4, Fig. 3; and

Fig. 5 is a sectional detail on the line 5—5, Fig. 3, the spring plank being omitted.

In Fig. 1 of the drawing, the brake beams 10, 11 of any suitable construction are shown in association with the spring plank 12 or similar member of the car truck. Also there is shown two emergency safety bars each of which is composed of two bar members 13, 14, as shown more clearly in Figs. 2 and 3.

Preferably the bar members 13, 14 are similar to or identical with each other, for economy in manufacture, as each bar member may take the place of the other member and as each of them may be placed in using position without regard to any special feature of construction of the other bar member. Each bar member is preferably composed of flat lengths of metal positioned edgewise vertically underneath the spring plank, when they are in using position. Bar member 13 comprises offset parallel end portions 16, 17 which are connected by an intermediate deflected portion 15. The bar member 14 comprises similar and corresponding portions 18, 19 and 20, so that, in transportation from the mill, the two bar members and any number of them may be placed flat against one another so as to take up a minimum of space.

The inner portions 17, 20 of the bar members are especially formed and united in order to provide a single safety bar when in use. It will be seen clearly from Fig. 2 from the broken lines that the inner ends of the end portions 17, 20 of the bar members are deflected and are inclined in opposite directions away from the vertical plane which the safety bar 13, 14 assumes when in using position, and that the inner extremities are overlapped. These deflected portions 17, 20 will be again referred to later on.

From one side of spring plank 12 there depends a supporting bracket 21 and from the other side a supporting bracket 22. These brackets are provided with inwardly turned upper ends 23 which engage over the upper edges of the spring plank, the brackets being secured in position by means of rivets 24. As shown in Figs. 2, 3 and 4 the lower ends of the brackets 21, 22 are respectively formed with inwardly extending flanges or cheek portions 25, 26, fashioned somewhat as shown in the aforesaid patent. The proportions of the parts of the brackets are such that the upper edges of the cheek portions 25, 26 will have a firm bearing contact with the under surfaces of the spring plank,

for the sake of solidity, and hence rigidity. Between the cheek portions, the outer face portion of each bracket is formed with an opening or vertical slot 27, which is located between the cheek portions of each bracket, and defines the distance at which the cheek portions of each bracket are spaced apart.

In applying the two-piece safety bar to the spring plank, the inner end portions 17, 20 of the bar members are first inserted through the corresponding openings or slots 27 therefor, so as to pass between the cheek portions of the brackets, and to be in bearing relation therewith. When these bar members 13, 14 are in proper position, locking pins 28 are passed through registering openings in the cheek portions and the portions 17, 20 of the bar members. In doing so, yieldable self-locking keepers 29 mounted in the locking pins 28 will act to hold the locking pins in place. Such a form of locking pin is well known. Thereby the two bar members 13, 14 will be detachably supported in using position upon the brackets, with the upper edges of the inner portions 17, 20 thereof bearing transversely upon the entire width of the bottom surface of the spring plank 12. Such relation between the brackets, the bar members and the spring plank tends to rigidity.

After the bar members 13, 14 have been separately detachably connected with the supporting brackets 21, 22, with their deflected inner ends in overlapped relation and bearing squarely upon each other, a U-shaped straddle member 30 is passed upwardly over the overlapped ends of the bar members, so that the upper edges of the bar members and of the straddle member 30 will be substantially in one plane and said edges will all bear upon the bottom surface of the spring plank. The straddle member 30 and the inner ends of the bar members are provided with holes which are adapted to register, as clearly shown in Fig. 5, and when registered a headed connecting pin 31 is passed through and retained in position by means of a key or cotter pin 32, and thereby the overlapped ends of the bar members are firmly united together so as to practically form a single safety bar, adapted to be rigidly supported as well as a safety bar of one piece.

Obviously the illustrated and described invention is susceptible to modification as will be apparent to those skilled in the art, without departing from the invention as defined in the appended claims.

What I claim as new is,—

1. In auxiliary supporting means for brake beams, the combination with a truck member, of two bar members with overlapped inner ends and extending outwardly beyond the truck member, means for separately, detachably supporting the bar members from the truck member at points below such truck member, a U-shaped member straddling the overlapped ends, and means for rigidly connecting the overlapped ends and U-shaped member, whereby to unite the two bar members and provide a single safety bar.

2. In auxiliary supporting means for brake beams, the combination with a truck member, of two bar members with overlapped inner ends and extending outwardly beyond the truck member, supporting brackets rigidly attached to and depending from the truck member, removable locking pins separately detachably connecting the bar members with the lower ends of the brackets, a U-shaped member straddling the overlapped

ends, and means for rigidly connecting the overlapped ends and U-shaped member, whereby to unite the two bar members and provide a single safety bar.

3. In auxiliary supporting means for brake beams, the combination with a truck member, of two bar members with overlapped inner ends and extending outwardly beyond the truck member, brackets carried by the truck member and each provided with spaced apart cheeks at opposite sides of an opening therein, the cheeks extending inwardly under the truck member and the bar members extending through the openings and between the cheeks, removable locking pins separately detachably connecting the bar members with the cheeks, a U-shaped member straddling the overlapped ends, and means for rigidly connecting the overlapped ends and U-shaped member, whereby to unite the two bar members and provide a single safety bar.

4. In auxiliary supporting means for brake beams, the combination with a truck member, of two bar members with overlapped inner ends and extending outwardly beyond the truck member, means for separately, detachably supporting the bar members from the truck member, a U-shaped member straddling the overlapped ends, and pins passing through the straddle member and connecting the overlapped ends and U-shaped member, the pins extending longitudinally of the truck member, whereby to unite the two bar members and provide a single safety bar.

5. In auxiliary supporting means for brake beams, the combination with a spring plank, of two bar members having meeting inner ends and extending outwardly beyond the spring plank, means for separately, detachably supporting the bar members from the spring plank and with their inner end portions in contact with the bottom surface of the spring plank throughout, the meeting ends of the bar members overlapping, a U-shaped member straddling the overlapped ends and having its upper edges in contact with the bottom surface of the spring plank, and means for detachably connecting the overlapped ends and U-shaped member so as to provide a single safety bar.

6. In auxiliary supporting means for brake beams, the combination with a spring plank, of two bar members having meeting inner ends and extending outwardly beyond the spring plank, means for separately, detachably supporting the bar members from the spring plank and with their inner end portions in contact with the bottom surface of the spring plank throughout, the meeting ends of the bar members overlapping, a U-shaped member straddling the overlapped ends and having its upper edges in contact with the bottom surface of the spring plank, and a removable keyed on pin for detachably connecting the overlapped ends and U-shaped member so as to provide a single safety bar.

7. In auxiliary supporting means for brake beams, the combination with a truck member, of two, similar, bar members of flattened form set vertically edgewise and extending outwardly in one plane beyond the truck member, means for separately, detachably supporting the bar members in such position from the truck member, the inner ends of the bar members being deflected in opposite directions from such plane and being overlapped, a straddle member over the deflected inner ends of the bar members,

and a pin passing through the straddle member and the inner ends, so as to provide a single safety bar.

8. A safety bar comprising two, similar, bar members of flattened form, positioned flatwise with respect to each other and having their main portions extending in one plane, the inner ends of the bar members being deflected in opposite directions from and inclined to such plane and being overlapped, and means for detachably connecting the overlapped ends.

9. In auxiliary supporting means for brake beams, the combination with a spring plank, of two bar members having overlapping inner ends and extending outwardly and deflected upwardly beyond the spring plank, brackets for supporting the bar members from the spring plank on edge and with their inner end portions in contact with the bottom surface of the spring plank, and keepers or pins for detachably connecting the bar members to the brackets to provide a safety bar.
